UNITED STATES PATENT OFFICE.

BERNARD ACKERMAN, OF NEW YORK, N. Y.

DOOR BOLT.

Application filed May 11, 1925. Serial No. 29,554.

To all whom it may concern:

Be it known that I, BERNARD ACKERMAN, a citizen of the United States of America, and a resident of the city of New York, 5 borough of Manhattan, in the county and State of New York, have invented a new and Improved Door Bolt, of which the following is a description.

My invention relates to a door bolt and 10 particularly to a door bolt adapted to be carried by the door and to engage the floor in a way to positively prevent the opening of the door or even limited movement thereof.

15 The general object of my invention is to provide a door bolt of the indicated character which may be conveniently manipulated to dispose it in an upstanding position on the door to be carried by the latter or to 20 an oblique position in firm engagement with the floor and the door.

More specifically, the invention has for its 25 object to provide a bolt of the indicated type possessing the maximum strength and embodying few elements of simple form.

Reference is to be had to the accompanying drawings forming a part of this specification, it being understood that the drawings are merely illustrative of one example 30 of the invention.

Figure 1 is a view partly in section and 35 partly in side elevation of a door bolt embodying my invention showing the same affixed to the door, the dotted lines indicating the locking position of the bolt;

Figure 2 is a front elevation of my improved door bolt, with the floor socket in vertical section, the section as indicated by the line 2—2 in Figure 1;

40 Figure 3 is a partly sectional side elevation showing a fragment of the bolt and door in the locking position;

Figure 4 is a horizontal section on the line 4—4, Figure 1.

45 In carrying out my invention in accordance with the illustrated example I provide a bolt composed of telescoping sections, the one section 10 being externally threaded and engaging internal threads 111 in the other section 11. At the opposite end from the section 10 the section 11 has a plug 12 closing the same and said plug being formed with a rounded end and having a threaded shank 112 engaging the internal threads 111.

50 At the end of the threaded section 10 a terminal 13 is formed which in practice is

made flat to better engage the floor socket 24 hereinafter referred to, said terminal 13 having at the end thereof at one side a beveled surface 14 to contact with and lie 60 parallel with the bottom of the floor socket 24.

The bolt section 11 is turnable and slideable in a collar 15 having trunnions 16 rockable in arms 17 on a bracket 18 adapted to 65 be secured by any suitable fasteners to the door A.

On the bracket 18 or otherwise rigidly secured to the door is a bolt holder adapted to receive the plug 12 of the bolt when the latter is in upright position alongside the door as in Figures 1 and 2. The plug 12 has studs 20 at diametrically opposite sides adapted by a vertical movement of the bolt to engage the bevelled cam surfaces 22 at 75 the upper end of flange 23 on the bolt holder 19. The socket 24 has a bevelled under-cut indicated at 25, Figure 1, so that when the bevelled surface 14 of the bolt terminal 13 rests at the bottom of the socket 24 the opposite side edge of the terminal 13 will lie against and be parallel with the undercut bevel 25.

With a bolt embodying my invention such as shown for example in the drawing, the bolt normally will be carried by the door A and will be disposed in the upright position with the studs 20 resting in recesses 21 between the bevels 22 so that the holder 19 will thus sustain the bolt. When the door 90 is to be locked the bolt is lifted out of engagement with the holder 19 by vertically sliding the section 11 in the collar 15 until the plug 12 clears the flange 23. The bolt may now be rocked to the dotted line position of Figure 1 which will dispose a plug 12 at the upper end and the terminal 13 in the socket 24; the tubular section 11 is now turned to cause the telescoping section 10 to move downwardly thereby increasing the 100 total effective length of the bolt. At this time the plug 12 is pressed firmly in a recess 26 at the under side of the abutment 27 on the base or bracket plate 18. When the door is to be released, the section 11 is 105 reversely turned on the section 10 so that the latter is moved partly into the section 11, thereby reducing the total effective length of the bolt and permitting the terminal 13 to swing out of the socket 24 after which the bolt is swung vertically on the bracket arms 17 from the dotted line position to the

95

100

105

110

upright position and then permitted to gravitationally drop through the collar 15 until the studs 20 engage the holder 19 at the recesses 21.

- 6 In order to indicate when the bolt has been shortened sufficiently to permit the section 10 to be disengaged from the floor socket 24, I provide a member 28 on the collar 15, said member being adapted to receive the contact 10 of one or other of the studs 20 when the bolt has been shortened sufficiently for said studs 20 to reach the plane of the member 28.

15 It will be noted from the dotted line position of the bolt as indicated in Figure 1 that the upper and lower ends of the bolt in the locking position exert a thrust against surfaces in parallel planes. Thus, the axis of the bolt is perpendicular to the thrust receiving surfaces in the socket 24 and abutment 26.

20 I would state furthermore that while the illustrated example constitutes a practical embodiment of my invention, I do not limit myself strictly to the exact details herein 25 illustrated, since, manifestly, the same can be considerably varied without departure from the spirit of the invention as defined in the appended claims.

Having thus described my invention, I 30 claim:

1. A door bolt including telescoping bolt sections having threaded engagement with each other, an element in which one of said sections has turning and sliding movement, 35 means to rockably mount said element on a door to permit the bolt sections to move to an approximately upright position adjacent the door or to oblique position for engagement with a floor adjacent the door bolt

holding means, and means to sustain said 40 bolt holding means on the door.

2. A door bolt including telescoping bolt sections, an element in which one of said sections has turning and sliding movement, means to rockably mount said element on a 45 door to permit the bolt sections to move to an approximately upright position adjacent the door or to oblique position for engagement with a floor adjacent the door bolt-holding means, and means to sustain said 50 bolt-holding means on the door.

3. A device of the class described including a bolt formed in telescoping sections to vary the total effective length of the bolt, and means to turnably and rockably hold 55 said bolt on the door to permit the bolt to assume a position alongside the door or an oblique position to engage a floor; together with a bolt-sustaining means affording support for said bolt at the lower end when the 60 bolt is in the first position.

4. A door bolt including an externally threaded bolt section, an internally threaded bolt section engaged by the first section, a collar in which the second section is slidable 65 and turnable, and means to support said collar on a door; together with a holder adapted to be carried by the door and affording a rest for the lower end of the bolt, said holder having a flange formed with 70 recesses as well as with bevelled surfaces above the recesses, and studs on the bolt adapted to be accommodated in said recesses, said collar having a member adapted to be engaged by said studs with the relative turning of the bolt sections in a direction to shorten the total length of the bolt. 75

BERNARD ACKERMAN.
